UNITED STATES PATENT OFFICE.

FRANK M. A'HEARN, AND PAUL S. WINTER, OF GREENVILLE, PENNSYLVANIA.

BOILER-Injector CHECK-TURRET.

1,006,709.

Specification of Letters Patent. Patented Oct. 24, 1911.

Application filed March 11, 1911. Serial No. 613,714.

To all whom it may concern:

Be it known that we, FRANK M. A'HEARN and PAUL S. WINTER, citizens of the United States, and both residing in Greenville, in the county of Mercer and State of Pennsylvania, have invented certain new and useful Improvements in Boiler-Injector Check-Turrets, of which the following is a specification.

10 Our invention relates to injector check turrets of the kind employed to inject feed-water into the steam space of a boiler, and our invention consists in an improved form of spraying nozzle which more effectively distributes the feed-water within the boiler.

15 In the accompanying drawings, Figure 1 is a top plan view of an injector check turret embodying our improvements. Fig. 2 shows a side elevation thereof. Fig. 3 is a view 20 partly in side elevation and partly in vertical section of the same applied to the shell of a boiler. Fig. 4 is a detail view in vertical section of the spraying nozzle. Fig. 5 shows a transverse section thereof. Fig. 6 25 shows a plan of the annular flange on the turret casing which receives the attaching bolts. Fig. 7 shows a transverse section through a steam boiler with our improvements applied. Fig. 8 shows in top plan 30 the dry pipe of a boiler and illustrates how the feed-water is distributed by our improved spraying device.

The casing A is formed with a valve chamber A' which communicates with a passage B extending through the base B' of the casing. This base is prolonged by a part B² of smaller diameter which extends into the boiler C, as indicated in Fig. 3. Between the parts B' and B² there is a shoulder b which is tapered and slightly rounded and fits tightly a corresponding socket in the boiler shell c. The part B' is formed with an annular flange B² provided with holes b' to receive bolts which engage the shell of the boiler and tightly secure the casing thereto. The casing shown has on opposite sides bosses D formed with threaded openings D' which, as shown in Fig. 7, are coupled to check-valves E, of usual construction, communicating with the feed-water pipes F through which the feed-water is fed or injected in well known ways.

55 The top G of the chamber A' is preferably formed as shown in Fig. 3, i. e., the top wall is inclined downwardly from the

top of the casing, has a central opening, and is threaded at g to receive the lower threaded end of the bonnet H through which extends the valve stem I having a threaded connection at i with the bonnet. The valve stem 60 carries a handle K and a valve L which is adapted to fit a valve seat l formed at the bottom of the chamber A' at the top of the part B' of the casing. Suitable packing M for the valve stem may be provided and the 65 construction is such that by operating the handle K the valve may be fully opened, as indicated in Fig. 3, or closed tightly upon the valve seat l to thus cut off communication simultaneously between the boiler and 70 both feed pipes. When this is done either or both the check valves E or any of the other parts in the feed-water system may be repaired.

The lower end of the casing A which projects into the boiler is formed to provide a spraying nozzle of improved construction. The passage B communicates with lateral discharge openings N on opposite sides of the nozzle and these openings, as shown in 75 Figs. 7 and 8, are arranged on opposite sides of the longitudinal central line of the boiler. The openings N are substantially semi-circular. Their upper walls n are straight or horizontal, while their lower walls n' are inclined downwardly meeting at a knife edge n² parallel with the longitudinal central plane of the boiler. Each opening N is 80 preferably divided by a vertical web n³ into two parts and the lower walls n' in addition to being inclined are also preferably curved 85 as shown in Fig. 2. Preferably the walls n' are inclined at an angle of 30° to the horizontal but this inclination may be varied to 90 suit different conditions. By the construction shown each opening N becomes more contracted as the curved lower walls extend upwardly and the construction is such as to cause part of the entering water to deflect 95 toward the ends of the boiler as well as to proceed outward toward the sides thereof. The nozzle thus constructed acting in conjunction with gravity prevents the feed-water from being thrown against the inside 100 of the boiler shell and clears the dry pipe. 105 After leaving the nozzle the feed-water is sprayed and spreads into two fan shapes as indicated in Fig. 8. In this condition it passes through the steam at the top of the boiler and becomes thoroughly heated before 110

being deposited upon the water in the boiler and is widely distributed at the water level in an area which is approximately circular and of a diameter about equal to the width 5 of the water level inside the boiler. In this way no currents of cold water can be formed by the entering feed-water and no cold water can come in contact with the boiler shell.

Any desired number of turrets may be 10 used, each of which may be connected with one or with a plurality of feed pipes.

We claim as our invention:

1. A spraying nozzle for injector check turrets having two horizontally flaring open- 15 ings provided with inclined lower walls

which meet at their upper ends in a horizontally arranged knife edge.

2. A spraying nozzle for injector check turrets having horizontally flaring openings provided with downwardly inclined walls 20 having curved outer edges, the upper portions of said walls being arranged in intersecting planes.

In testimony whereof, we have hereunto subscribed our names.

FRANK M. A'HEARN.
PAUL S. WINTER.
